(57) **CLAIM**

The ornamental design for an egg box, as shown and described.

DESCRIPTION

FIG. 1 is a first perspective view of an egg box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a sectional view thereof, taken along the dot-dash lines 9-9 in FIG. 5; and,

FIG. 10 is an exploded view of the egg box thereof.

The broken lines shown in the drawings are for the purpose of illustrating portions of the egg box and forms no part of the claimed design. The dash-dash broken lines shown in FIG. 5 indicate the plane upon the sectional view is taken and form no part of the claimed design.

1 Claim, 10 Drawing Sheets
